[57] CLAIM

The ornamental design for a belt-type garment for carrying tennis balls, as shown and described.

DESCRIPTION

FIG. 1 is a perspective view of a belt-type garment for carrying tennis balls showing my new design;
FIG. 2 is a front elevational view thereof, the belt being shown as extended;
FIG. 3 is a top plan view thereof;
FIG. 4 is a rear elevational view thereof, and
FIG. 5 is a perspective view of a second embodiment thereof.

FIG. 1
